UNITED STATES PATENT OFFICE.

OTTO C. KADE, OF CHICAGO, ILLINOIS, ASSIGNOR TO MELCHIOR BROS.
FURNITURE COMPANY, OF CHICAGO, ILLINOIS.

CORNER OR FASTENING FOR SHOW-CASES.

SPECIFICATION forming part of Letters Patent No. 722,588, dated March 10, 1903.

Application filed August 23, 1902. Serial No. 120,831. (No model.)

To all whom it may concern:

Be it known that I, OTTO C. KADE, a citizen of the United States, residing at Chicago, in the county of Cook and State of Illinois, have 5 invented new and useful Improvements in Corners or Fastenings for Show-Cases, of which the following is a specification.

This invention relates to show-case corners; and the primary object of the same is to provide a simple and effective means for fastening glass plates used in forming show-cases or analogous devices at their intersecting angles or corners without weakening the said plates or interfering with a tight fit of the edges thereof and having such reliable securing characteristics that the usual rails or molding, as well as frames for holding glass plates at points intermediate of their edges, may be entirely dispensed with, and thus permit 15 the production of an attractive show-case of a strong and durable nature with a minimum cost in the manufacture of the same.

The invention consists in the construction and arrangement of the several parts, which 20 will be more fully hereinafter described and claimed.

In the drawings, Figure 1 is a perspective view of a portion of a show-case composed of glass plates and illustrating one of the improved corners applied thereto. Fig. 2 is a section through the corner of a portion of the show-case shown by Fig. 1 and the improved device taken in a diagonal plane. Fig. 3 is a detail perspective view of the improved 25 corner or fastening, showing the parts thereof separated.

Similar numerals of reference are employed to indicate corresponding parts in the several views.

40 The numerals 1 and 2 designate side and end plates, and 3 a top plate, of a show-case, said plates being of glass and having the exposed edges suitably finished. To protect the side and end plates, the edge portion of 45 the top plate, at the sides and ends thereof, extends over the members of the show-case below, and thereby also forms an ornamental case. The improved corner or fastening consists of a stiff-metal corner-socket 4, shaped 50 to embrace a portion of the side, end, and top plates 1, 2, and 3 and also having a hol-

low bead 5 to compensate for the edge extension of the top plate 3. The corner or fastening 4 is of approximately triangular form, and extending downwardly and inwardly at 55 an angle of inclination from the upper angle 6 of the improved device is a bolt-rod 7, which is passed through suitable small openings 8, formed in the adjacent portions of the plates 1, 2, and 3. A triangular clamping-block 9 60 is fitted over the inner end of the bolt-rod 7, said block having an outwardly-flared socket 10 to permit it to be applied over the said bolt-rod and remain in loose connection with said rod until a clamping-nut 11 is applied to 65 the inner screw-threaded extremity of the bolt-rod and brought firmly to bear against the inner face of the block 9. When the nut 11 is applied and contacts with the block 9, the latter is drawn upwardly into place and 70 firmly bears at its three sides, respectively, against the side, end, and top plates 1, 2, and 3 and is located far enough away from the intersecting terminations of said plates at the angle thereof forming the corner to prevent 75 fracture of the plates. When the nut 11 is turned against the block 9 and the latter caused to closely bear against the inner side of the plates adjacent to their angle of intersection, the improved corner or fastening 4 is 80 tightly drawn against the outer portions of the said plates, as clearly indicated by Figs. 1 and 2. Owing to the approximately triangular form of the socket or fastening 4, the plates 1, 2, and 3, adjacent to their angles of 85 intersection, are immovably held, and the side and top members of the socket 4 closely bear against said plates, and the hollow bead snugly receives the extended edge portions of the top plate 3. By this means all the parts 90 of the improved corner-fastening are reliably and immovably held in engagement with the corner of the case, and after all the corners are applied to a case the latter is held rigid with a strength equal to that of cases employing frames or moldings to receive the edges 95 of the glass plates.

The improved device is also very convenient in view of the rapidity with which it can be applied or detached in setting up or taking down show-cases, and as it does not require the knowledge of a skilled person to ap-

ply the corner the show-case composed of glass plates without side and end frames or moldings can be reduced and packed closely during transportation or storage and afterward easily set up in operative position.

It is proposed to make all the parts of the improved corner or fastening of metal and suitably ornament the same, particularly the socket 4, and for the purpose of practically 5
10 applying the clamping-block 9 to the plates the side edges thereof are beveled or cut at an angle of inclination, as clearly shown by Fig. 3. As a further means of facilitating the application of the clamping-block 9 the 15 inner portions of the corners are cut away to form curved bevels, as at 12, and in view of the formation of the socket 10, which is located in the center of the block 9, the latter will automatically adjust themselves to the 20 inner faces of the plates 1, 2, and 3 when applied.

To accommodate the application of the improved corner or fastening to cases of various sizes, changes in the proportions, dimensions, 25 and minor details of construction may be resorted to without in the least departing from the principle of the invention.

Having thus fully described the invention, what is claimed as new is—

1. A corner or fastening of the class set 30 forth comprising an approximately triangular socket having depending sides and a top member and also provided with a bolt-rod extending from the upper angle thereof at a downward inclination, a triangular-shaped 35 clamping-block to loosely fit over the said bolt-rod, and a clamping-nut removably engaging the said rod.

2. A corner or fastening of the class set forth comprising a socket to fit over the exterior of the corner of a case or the like and provided with an inwardly-extending and downwardly-inclined bolt-rod, and means for engaging the said bolt-rod within the plane of the socket to firmly hold the latter in applied position.

3. A corner or fastening of the class set forth, comprising a socket member of approximately triangular form and having an upper surrounding hollow bead, and means for securing the said socket in applied position.

In testimony whereof I affix my signature in presence of two witnesses.

OTTO C. KADE.
